(57) **CLAIM**

The ornamental design for a vehicle rear bumper cover, as shown and described.

DESCRIPTION

FIG. 1 is a front elevational view of a vehicle rear bumper cover showing our new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a top, front, and left side perspective view thereof;
and,
FIG. 7 is a bottom, front and left side perspective view thereof.

Portions of the vehicle rear bumper cover shown in half-tone shading and surrounded by broken lines form no part of the claimed design.

1 Claim, 7 Drawing Sheets
